UNITED STATES PATENT OFFICE.

ALBERT H. SISSON, OF CHICAGO, ILLINOIS, ASSIGNOR TO FORSYTH BROTHERS COMPANY, OF CHICAGO, ILLINOIS, A CORPORATION OF ILLINOIS.

CAR CONSTRUCTION.

1,112,856.

Specification of Letters Patent.

Patented Oct. 6, 1914.

Application filed October 12, 1911. Serial No. 654,308.

To all whom it may concern:

Be it known that I, ALBERT H. SISSON, a citizen of the United States, residing at Chicago, in the county of Cook and State of Illinois, have invented certain new and useful Improvements in Car Constructions, of which the following is a specification.

My invention relates to car constructions, and refers particularly to an improved type 10 of car frame and sheathing used in connection therewith.

I have found that it is particularly advantageous in order to obtain a car of light and strong construction to employ supporting members which are suitably disposed on the sides of the car. These supporting members may consist of plates or sheathing formed so as to have the function of a supporting framework. When the sheathing is 20 formed in this manner, reinforcing angle irons or the like may be used in conjunction with the supporting portions of the sheathing.

A further advantage of my invention consists in the manner of forming the upper portion of the sheathing, the lower portion of the sheathing and the car post. These members may be formed in one or more pieces. The formations are of such a character as to permit the use of exceptionally light material, while affording the maximum strength.

These and other advantages of my invention will be more readily understood by reference to the accompanying drawings, which show preferred embodiments of my improvements, and in which—

Figure 1 is a side elevation of a portion of a car. Fig. 2 is a perspective showing a 40 portion of the side of a car, in which a somewhat modified construction is used from that shown in Fig. 1; Fig. 3 is a sectional view on line 3—3 of Fig. 2. Fig. 4 is a perspective sectional view on line 4—4 of Fig. 2. Fig. 5 is a perspective and sectional view of the lower portion of the car sheathing and the parts associated therewith; Fig. 6 is a 45 view similar to Fig. 5, but showing a modified construction; and Fig. 7 is a view similar to Fig. 5, but showing a still further modified construction.

In the construction shown in Fig. 1, the car is shown as having a roof 10 and a plurality of side sheathing plates 11. These 55 sheathing plates are formed with the diag-

nally disposed truss members 12 and the vertical members 13. Between the vertical members 13 and the diagonal truss members 12 are formed the panels 14. If so desired a window 15, a door 16, or the like, may be 60 formed between the vertical members 13, 13. The diagonal truss members 12 are preferably reinforced by suitable angle irons or the like, and inside of the vertical members 13 may be located the car posts. 65

In the construction illustrated in Fig. 2 a plate 17 is formed with its portions 18 projecting laterally and the portion 19 projecting downwardly and extending on its lower part over the plate 20 located on the outside of the car post; said lower plate 20 may, as shown at 20^a be out-set so as to have the plates 17 and 20 in the same plane. If desired, however, the plate 17 may be formed integrally with the plate 20 or with the 70 plates 20 and 21, or plate 17 may be formed separately from plates 20 and 21, the latter being formed integrally with each other. The outer sheathing 21 below the belt rail 22 is formed with the obliquely disposed 80 portions 23 between which are the panels 24. Within the obliquely disposed members 23 of the outer sheathing 21 are placed the angle irons 25, each of which may extend upwardly within the car post; represented 85 as a whole by 26. Each angle iron passes downwardly within an obliquely disposed member, to which it is fastened by rivets 27 and is also fastened at its lower angular portion 28 to the angle iron 29. The plates 90 17 are fastened to the car posts 26 by means of the angle irons by straps 30, to which the plates 20 of the car posts 26 and the plates 17 are riveted. If desired, the plates 20 of the car posts 26 may be suitably bent to 95 form sash guides for the window sashes 31. As clearly shown in the right-hand portion of Fig. 2, the plate 20 extends preferably upwardly within the lower portion 19 of the plate 17, although the edges of these plates 100 might abut each other. The adjacent edges of the portions 18 of the plates 17 are fastened to the upwardly extending post 32, and, if desired, a reinforcing plate 33 may also be used. 105

In Fig. 2 I have shown the angle irons 25 as the strengthening means for the obliquely disposed members 23 of the sheathing 21.

In Fig. 3 I have shown an enlarged sec- 110

tional view taken on line 3—3 of Fig. 2 in which 31^a denotes the upper glass provided with bearing or spacing blocks or strips 31^b and bearing against the inwardly extending lips 31^c of the flanges 31^d, the glass being retained in position by means of the glazing strips 31^e having screws 31^f. Beneath the lower margin of the glass 31^a is the cross-bar 31^g which is secured to the lower portions 19 of the plates 17, and rests upon the front portion of the outer member 31^b. The cross-bar 31^g is provided on its inner face with flanges 31^h which are riveted to the flange 31^d, which latter flange is also riveted to the lip 31^c of the flange 31^d and to the lips 17^a of the flange 17^b.

In Fig. 4 I have shown an enlarged perspective and cross-sectional view through the post construction on the line 4—4 of Fig. 2 in which the members and their manner of assembling with each other are clearly indicated.

In Fig. 5 I have shown a modified form of construction over that shown in Fig. 2 in which the members 23 are reinforced by a suitably formed plate member 34, the upper and lower edges 35 and 36 of which are fastened to the sheathing 21 by means of the rivets 37.

30 In the construction shown in Fig. 6 I employ an inner sheathing 38 in addition to the outer sheathing 21. Between these sheathings is located the intermediate plate 39, which engages at its upper edge the horizontal portion 40 of the strengthening member 41. This intermediate plate 39 extends downwardly to the block 42, which, in turn, is fastened to the angle iron 29, separated at its lower portion from the outer sheathing 21 by means of the block 43. Within the obliquely disposed member 23 are the suitably bent reinforcing members 44, which are held in position between the member 23 of the outer sheathing 21 and the corresponding member 45 of the inner sheathing 38. The members 44, the intermediate plate 39 and the outer and inner sheathings 21 and 38 are fastened together by means of rivets 46.

50 In the construction shown in Fig. 7 no intermediate plate 39 is used, but a suitably bent reinforcing member 47 is located between the member 23 of the outer sheathing 21 and the member 45 of the inner sheathing 38, while a similarly bent reinforcing member 48 is used within the belt rail to retain the outer sheathing 21 and the inner sheathing 38 in the appropriate positions.

30 It will be apparent to those skilled in the art that many changes could be made in

the detailed construction of the parts which I have described without departing from the spirit or scope of my invention.

What I claim is:

1. In a car construction, the combination of a sheathing having obliquely disposed strengthening members integrally formed therein, and reinforcing means cooperating with said members, substantially as described.

2. In a car construction, the combination of a belt rail, a sheathing extending below said belt rail, said sheathing having strengthening members integrally formed therein, a car post, and a separate sheathing for said car post, substantially as described.

3. In a car construction, the combination of a belt rail, a sheathing extending below said belt rail, said sheathing having obliquely disposed strengthening members formed therein, a car post, and a separate sheathing for said car post, substantially as described.

4. In a car construction, the combination of a sheathing having obliquely disposed strengthening members formed integrally therewith at an angle to each other, and reinforcing means within said strengthening members, substantially as described.

5. In a car construction, the combination of a belt rail, a sheathing extending below said belt rail and having obliquely disposed strengthening members formed therein, a car post having a window opening adjacent thereto, a second sheathing for said car post, and a third sheathing above said window opening and having a portion extending downwardly over said car post, substantially as described.

6. In a car construction, the combination of a belt rail, a sheathing extending below said belt rail and having obliquely disposed strengthening members formed therein, and reinforcing means within said strengthening members, said reinforcing means extending upwardly into said car post, substantially as described.

7. In a side construction for railway cars, having a plurality of window openings, of a sheet metal plate disposed between a pair of such window openings, edges of such plate constituting portions of the margin of the window openings, said edges having flanges integral with the plate and lying in an offset parallel plane and adapted for the reception and retention of the window sash.

ALBERT H. SISSON.
